CLAIM

The ornamental design for an insert golf putter head, as shown and described.

DESCRIPTION

FIG. 1 is a perspective view of the insert golf putter head. FIG. 2 is a right side elevational view of the insert golf putter head.

FIG. 3 is a left side elevational view of the insert golf putter head.

FIG. 4 is a rear elevational view of the insert golf putter head.

FIG. 5 is a front elevational view of the insert golf putter head.

FIG. 6 is a top plan view of the insert golf putter head; and, FIG. 7 is a bottom plan view of the insert golf putter head. The broken line showing of a fragmented shaft is for illustrative purposes only and forms no part of the claimed design.
